CLAIM

The ornamental design for a lid for cosmetic jar as shown and described.

DESCRIPTION

The file of this patent contains at least one drawing executed in color. Copies of this patent with color drawing(s) will be provided by the Office upon request and payment of the necessary fee.

FIG. 1 is a perspective view of a lid for cosmetic jar showing our new design;

FIG. 2 is a front view thereof, a rear side view thereof being symmetrical to the front view;

FIG. 3 is a top plan view thereof;

FIG. 4 is a bottom plan view thereof;

FIG. 5 is a right side view thereof, a left side view thereof being symmetrical to the right side view;

FIG. 6 is a cross-sectional view thereof taken along line 6-6 in FIG. 2;

FIG. 7 is a perspective view of an alternate embodiment thereof shown in color;

FIG. 8 is a front view thereof shown in color, a rear side view thereof being symmetrical to the front view;

FIG. 9 is a top plan view thereof shown in color;

FIG. 10 is a bottom plan view thereof shown in color;

FIG. 11 is a right side view thereof shown in color, a left side view thereof being symmetrical to the right side view; and, FIG. 12 is a cross-sectional view thereof taken along line 12-12 in FIG. 8.

The broken lines depict portions of the lid for cosmetic jar that form no part of claimed design.

In FIGS. 1 to 6, the oblique line shadings represent a portion that has transparency in the lid for cosmetic jar, the stipple shadings represent transparency gradient of the portion that has transparency in the lid for cosmetic jar, and the gray scale represents a portion that is a textile fabric with contrasting appearance and does not represent any particular color.

In FIGS. 7 to 12, the oblique line shadings represent a portion that has transparency in the lid for cosmetic jar, the gray scale represents transparency gradient of the portion
